US0D1050863S

(12) **United States Design Patent** (10) **Patent No.:** **US D1,050,863 S**
(45) **Date of Patent:** **** Nov. 12, 2024**

(54) **MAGNET HOOK**

(71) Applicant: **Ningbo Zhenhai Keyda Magnet Co., Ltd.**, Ningbo (CN)

(72) Inventor: **Mingmin Chen**, Ningbo (CN)

(73) Assignee: **Ningbo Zhenhai Keyda Magnet Co., Ltd.**, Ningbo (CN)

(**) Term: **15 Years**

(21) Appl. No.: **29/930,129**

(22) Filed: **Feb. 28, 2024**

(51) LOC (14) Cl. **08-11**

(52) U.S. Cl.

USPC **D8/367**

(58) **Field of Classification Search**

USPC D8/354, 355, 367, 372, 373, 376;
D12/223, 420

CPC F16B 47/003; Y10T 24/3484; Y10T
24/45115; Y10T 24/4523; Y10T 24/4755
